[57] ABSTRACT

A man's coat of (say) size 40 has a 40 inch horizontal breastline. The pattern for each (right and left) front panel of that coat has, at its upper rear corner, a triangular section, the sides edges of which extend up-

wardly from the breastline and correspond to the respective cut edges of the upwardly curved lower rear portion of the armhole and the corresponding portion of the rear side margin of the panel. The apex of the triangular section is flat, being characterized by a short top extending horizontally about one-fourth of an inch from one side edge of the triangular section to the other. The height of the triangular section from the breastline up to its flat top, which is actually equal to one-sixteenth of the breastline, is designated by tailors as "1/8th of the breastline." Thus, in coat sizes 38, 40, and 42 inches, the "triangular" section approximates 2 1/4 inches, 2 1/2 inches and 2 3/4 inches, respectively. A man's coat conventionally made from that pattern tends, when worn, to pull across the back between the lower halves of the armhole seams when the arms are outstretched and then crossed.

This objectionable pull is substantially reduced (if not completely eliminated) by substantially increasing the height of the triangular section to a value, which tailors would recognize as "one-fourth inch of the breastline" minus 1/2 inch more or less. In coat sizes 38, 40 and 42 inches, the increase approximates 2 inches, hence, the height of the section in the sizes mentioned approximates 4 1/4, 4 1/2, and 4 3/4 inches, respectively. These values represent increases of about 188 percent, 180 percent, and 173 percent of the conventional heights in the sizes mentioned.

Hereafter, the expressions "one-eighth BL," "one-fourth BL," etc., will be used to designate dimensions actually equal respectively to 1/16th of the breastline dimension, one-eighth of the breastline dimension, etc.

METHOD OF AND MEANS FOR IMPROVING THE ARMHOLE CONSTRUCTION OF A GARMENT

BACKGROUND OF THE INVENTION

1. Field of the Invention

This invention relates to improvements in men's coats and other like garments and, more particularly, to improvements in the armhole construction thereof.

2. Description of the Prior Art

Coat sizes of 38, 40, 42, etc. have breastline dimensions of 38 inches, 40 inches, 42 inches, etc. In cutting the pattern for a coat of any such size, the cut edge of the armhole is made to bottom against the breastline at a point where the upper end of the underarm dart intersects the breastline. From this bottom intersection point, the cut edge of the armhole curves laterally rearward and upward for a short distance, terminating at a point spaced about one-fourth of an inch horizontally from the cut edge of the rear side margin.

As a result, the upper rear corner of the pattern has a triangular section defined at its bottom by the breastline and at its opposite sides by the cut edges of the lower rear portion of the armhole and the corresponding portion of the rear side margin. The upper apex end of the triangular section is somewhat flat since the top extends horizontally about one-fourth of an inch from one side edge to the other.

With the pattern laid out, the cloth for the coat is cut in accordance with the pattern and the coat is constructed in accordance with conventional practices. Such a coat will have a back portion or "shoulder blade" strip extending from the lower curved half of one armhole seam (which is spaced from the cut line about $\frac{1}{4}$ inch) transversely across the shoulder blades to the lower curved half of the other armhole seam. With the best of tailoring, this "shoulder blade" strip will be subjected to a pull when the wearer of the coat extends his arms forwardly and crosses them.

SUMMARY OF THE INVENTION

Objects of the Invention

The principal object of the present invention is to provide a method of and a means for substantially reducing if not completely eliminating the objectionable pull on the shoulder blade strip of a man's coat.

Another important object is to accomplish the principal object without producing either any objectionable change in the tailoring of the coat or any objectionable alteration of its tailored appearance.

Statement of the Invention

I have discovered that, when the height of the "triangular" section is increased substantially beyond its conventional height, the tendency of the finished coat to pull across the shoulder blade strip is substantially reduced. When the triangular section is high enough, such pull is eliminated. Ordinarily, if the extension is increased to a dimension approximating one-fourth BL minus $\frac{1}{2}$ inch more or less, the pull on the shoulder blade strip will normally be eliminated for all practical purposes. This apparently is due to the fact that the curved portion of the armhole cut line, which forms the front boundary of said extension, shifts laterally forward and thus horizontally lengthens the shoulder blade strip sufficiently to reduce or prevent pull.

BRIEF DESCRIPTION OF THE DRAWING

The invention is illustrated in the accompanying drawing wherein:

5 FIG. 1 is an elevational view of the upper portion of the back of a man's coat or jacket, which is made with a right and left pair of allochiral front panels of the type exemplified by the left front panel shown in FIG. 2;

10 FIG. 2 is an enlarged front elevational view of the left front panel of a man's coat, jacket or like construction, which is to be buttoned or otherwise releasably secured along the center of its front face and which embodies the present invention, this view also representing the pattern for the left front panel; and

15 FIG. 3 is an enlarged fragmentary view of the upper part of the triangular section shown at the upper right rear corner of FIG. 2.

DESCRIPTION OF THE PREFERRED EMBODIMENT

One typical construction of a man's coat, jacket or like garment, which is to be buttoned or otherwise releasably fastened together along the center of its front face, includes 4 panels comprising: right and left back panels R and L; a right front panel (not shown) except for the fragmentary portion seen in FIG. 2; and a left front panel 1. The right and left front panels are allochiral panels, i.e., they are symmetrically alike but with their parts reversed in position like the parts of one's right and left hands. The same is true of the right and left back panels.

The present invention relates to an improvement in each of the front panels but, since they are allochiral, the invention is primarily described and illustrated only as applied to the left panel 1.

40 The left front panel 1 has a peripheral cut edge 2 and a $\frac{1}{4}$ inch wide marginal-edge or allowance portion extending between the peripheral cut edge 2 and the peripheral dotted allowance line 3. The $\frac{1}{4}$ inch wide marginal-edge allowance portion includes the following marginal edge allowance sections, viz: a shoulder section 5; a front neck section or gorge 6, to which the collar section (not shown) will ultimately be sewn; a front vertical section 7, the upper part of which includes the lapel; a bottom section 8; lower and upper left side sections 9 and 9A, which ultimately will be sewn to the back panel; and a left sleeve armhole section 10, located between vertical "construction" lines 11 and 12 and above breastline 13 except at the lowermost portion of the armhole. Actually the margins or "outlets" of the neck gorge 6 and front edge 7 are usually slightly wider than $\frac{1}{4}$ inch to permit desired trimming after these parts are sewn.

55 The cut edge 2 of the sleeve armhole section 10 fronts tangentially against the straight vertical construction line 12 and bottoms tangentially against horizontal breastline 13. The bottom of a straight vertical construction line 11 intersects the breastline 13 at a point 11A which is spaced about $\frac{1}{2}$ more or less from the cut edge 2 of the adjacent $\frac{1}{4}$ inch rear side margin 9. The bottom of vertical line 12 intersects the breastline 13 at a point 12A which is spaced from the cut edge 2 of rear side margin 9, a distance which varies with the coat size.

60 As noted before, the size of a man's coat is determined by the length of its horizontal breastline 13. Thus, coat sizes of 38, 40, 42, etc. have breastline

length dimensions of 38 inches, 40 inches, 42 inches, etc. The intersection point 12A (of vertical line 12 with the breastline 13) is spaced horizontally from the intersection point 13A (of the breastline 13 with peripheral cut edge 2 of the left side section 9) a distance equal to one-fourth BL plus about 1 to 1½ inches. Assuming that the left front panel illustrated is for a size 40 coat, then the breastline distance between intersection points 12A and 13A is equal to 5 inches plus approximately 1 to 1½ inches.

The left front panel 1 also has a conventional under-arm dart 15 and a waistline 16 spaced approximately 8½ inches below the breastline 13. The waistline 16 has a horizontal dimension equal to the breastline dimension minus one-eighth BL. Thus, in a size 40 coat, the waistline dimension equals 40 minus 2½ inches or 37½ inches. On the left front panel alone, the horizontal breastline dimension running from the vertical cut edge 2 of the front vertical section 7 to the vertical cut edge 2 of the rear vertical side section 9 approximates 16.6 inches in a size 40 coat while the corresponding horizontal waistline 16 dimension is about ½ inch smaller or about 16.1 inches.

In a conventionally cut left front panel 1, the upper apex end of the underarm dart 15 intersects both the breastline 13 and the cut edge 2 of sleeve armhole section 10 at one and the same point designated 10A, which is located about the bottom center of the sleeve armhole.

The upper rear corner of the front panel 1 includes a triangular section based on the breastline 13 and extending between the cut edges 2 of rear side marginal section 9 and the adjacent armhole marginal section 10. In a conventionally cut front panel 1, this triangular section extends from the dart-apex breastline-intersection point 10A horizontally rearward along the breastline through intersection point 11A to the breastline intersection point 13A with cut edge 2 of the rear side section 9, thence upwardly along cut edge 2 to a horizontal line 18 which extends from cut edge 2 to the upper end of a downwardly curved dotted line 19 and thence curves concavely downward along curved line 19 back to dart apex point 10A. The height of the conventional triangular section (or the distance between line 18 and breastline 13) is equal to one-eighth BL or 2½ inches in a size 40 coat.

With a triangular section one-eighth BL high, a coat, constructed in accordance with conventional practices, will have a "shoulder strip" 20, which, as seen in FIG. 1, extends from the lower half of one sleeve armhole seam transversely across the left and right shoulder blades to the lower half of the corresponding allochiral sleeve-armhole seam in the right front panel. With the best of tailoring, this "shoulder blade" strip 20 will be subjected to a pull and correspondingly placed under transverse tension when the wearer of the coat extends his arms forwardly and crosses them.

In accordance with my invention, the height of this triangular section is increased substantially beyond its conventional height. I have found that this substantial increase effects a substantial reduction in the tendency of the finished coat to be transversely tensioned along a "shoulder strip" corresponding to the strip 20, which, as seen in FIG. 1, extends from one seam line 3 to the other. Where the height of the triangular section is increased to a sufficient degree, such pull should be entirely eliminated. Ordinarily the height of that section

is increased to a dimension approximating "one-fourth of the breastline" minus ½ inch more or less. Thus, in a size 40 coat, the height of the triangular section is increased about 2 inches from the conventional 2½ inches to 4½ inches as indicated by horizontal line 18A. This makes the portion of the cut edge 2, which is common to both the sleeve armhole and the triangular section, move laterally forward from line 19, i.e., move toward the armhole so that the armhole cut edge 2 now extends from dart apex point 10A concavely upwardly along cut edge 2 to the upper inner end of line 18A of the triangular section. As a result, the extension is widened by the distance between the conventional cut edge, which is indicated by line 19, and the new rear armhole cut edge 2, which is spaced laterally forward from line 19. This moves the armhole seam line 3 accordingly which is to say it raises that seam line and moves it forwardly.

Before passing on, we note that rear side marginal section 9 is lengthened as indicated by 9A and that marginal sections 9A and 10 merge as they approach horizontal line 18A.

The present invention makes it possible to reduce in substantial measure and, for all practical purposes, eliminate the shoulder strip pull in a man's coat. In so doing, it does not produce any objectionable change in the tailoring of the coat or any objectionable alteration of its tailored appearance. If anything, its appearance may be enhanced.

While I have limited the description of the invention to a man's coat, it will be obvious that the invention may be applied to other garments which involve the same shoulder strip pull problem. Furthermore, this problem is found not only in men's coats and other like garments for men but also in women's coats and other like garments for women. The terms men and women are intended to include boys and girls. It is also found in so-called knits, the yield of which may render the conventional pull less objectionable.

While I have given the height of the conventional triangular section as being one-eighth BL, I have never known it to be higher. On the contrary, it may often be lower. Also, while (for coat sizes ranging from 38 to 42) I prefer to increase the height to a value equal to one-fourth BL minus ½ inch, it stands to reason that the present invention is not restricted thereto. The increase must be substantial enough to effect a substantial reduction in the pull across the shoulder strip. I have reason to regard an increase of 140 percent as being substantial. This would raise a conventional 2¼, 2½ and 2¾ inches height of size 38, 40 and 42 coats to 3.15, 3.50 and 3.85 inches respectively.

The height of the triangular section should not be increased to a point where it provides extra width from shoulder to shoulder above the area of the shoulder strip pull. Normally it should not be increased above the sleeve notch conventionally provided in the adjacent back panel. Subject to those limitations, the conventional height may be increased as much as 210 percent.

In other words, the height may be increased from 140 to 210 percent (in coat sizes ranging from 38 to 42) or from one-fourth BL minus 1½ inches to one-fourth BL plus three-fourths of an inch. Increases in smaller and larger coat sizes should be correspondingly smaller and larger but, in any event, sufficient to effect a substantial reduction in the shoulder strip pull, yet insufficient to

provide excess width between the shoulders above the area of the shoulder strip pull.

From the foregoing, it will be appreciated that I have provided: an improvement in the pattern for the front panel of a coat-like garment; an improvement in the front panel itself; and an improvement in a coat-like garment.

My improvement in the pattern for the front panel of a coat-like garment relates to a pattern having vertical front-side and rear-side marginal edges 2 and a horizontal breastline 13 extending from one side edge 2 to the other and separating the rear edge 2 into an upper edge part extending slightly above the breastline 13 and a lower edge part extending substantially below the breastline, the upper rear corner of the pattern having a sleeve hole bottoming at 10A against the breastline 13 with the lower rear portion of the sleeve hole defined by a rearwardly and upwardly extending concavely-curved pattern edge, (extending from 10A to 18A). This improvement comprises a triangular section based on the breastline 13, defined by and between said concavely-curved sleeve-hole edge 2 and the upper edge part of the rear-side marginal edge 2, and having a horizontal top 18A, a height from the breastline to its top of increased value such that it is substantially greater than one-eighth BL and a corresponding increase in its width.

My improvement in the front panel itself may be described as comprising a front panel 1 cut in accordance with my improved pattern as described in the immediately preceding paragraph.

My improvement in a coat-like garment may be described as comprising: a pair of allochiral right and left front panels which are described in the immediately preceding paragraph; a pair of allochiral right and left back panels R and L; and means for securing said right front panel to said right back panel R, said left front panel 1 to said left back panel L and said right back panel R to said left back panel L to form the corresponding portion of a coat-like garment, and to provide the back thereof with a shoulder strip 20 having an increased length corresponding to the increase in width of the triangular sections on said right and left front panels. The right and left front panels can, of course, be cut from the same pattern and then placed in allochiral arrangement relative to each other. The allochiral back panels are conventional. The means for securing the panels is conventional. However, when the panels are conventionally sewn together the shoulder strip 20 will be lengthened at each end by a distance corresponding to the spacing between line 19 and the adjacent curved armhole edge 2.

Having described my invention, I claim:

1. An improvement in the pattern for the front panel of a coat-like garment, said pattern having vertical front-side and rear-side marginal edges and a horizontal breastline extending from one marginal side edge to the other and separating the rear-side marginal edge into an upper vertical edge part extending slightly above the breastline and a lower vertical edge part extending substantially below the breastline, the upper rear corner of

the pattern having a sleeve hole bottoming against the breastline with the lower rear portion of the sleeve hole defined by a rearwardly and upwardly extending concavely-curved pattern edge, said improvement comprising:

A. a triangular section

1. based on the breastline,
2. defined by and between said concavely-curved sleeve-hole vertical edge and the upper edge part of the vertical rear-side marginal edge, and
3. having a horizontal top, a height from the breastline to its top of increased value such that it is substantially greater than one-eighth BL and a corresponding increase in its width.

15 2. An improvement in the front panel of a coat-like garment, said panel having vertical front-side and rear-side marginal edges and a horizontal breastline extending from one marginal side edge to the other and separating the vertical rear-side marginal edge into an upper vertical edge part extending slightly above the breastline and a lower vertical edge part extending substantially below the breastline, the upper rear corner of the panel having a sleeve hole bottoming against the breastline with the lower rear portion of the sleeve hole defined by a rearwardly and upwardly extending concavely-curved edge, said improvement comprising:

A. a triangular section cut in accordance with the triangular section pattern of claim 1.

30 3. An improvement in a coat-like garment, comprising:

- A. a pair of allochiral right and left front panels according to claim 2;
- B. a pair of allochiral right and left back panels; and

C. means for securing said right front panel to said right back panel, said left front panel to said left back panel and said right back panel to said left back panel

1. to form the corresponding portion of a coat-like garment, and
2. to provide the back thereof with a shoulder strip having an increased length corresponding to the increase in width of the triangular sections on said right and left front panels.

45 4. In the art of producing a coat-like garment, an improvement in the method of making a front panel having a triangular section, which is based on the breastline of the panel, which is defined on opposite sides by the lower rear curved edge portion of the armhole and the corresponding rear side edge portion of the panel respectively, which has a horizontal top approximating one-fourth of an inch and which normally has a height between the breastline and the top next exceeding one-eighth BL, comprising:

A. increasing the height of the triangular section substantially over one-eighth BL and correspondingly increasing the width of said section so as to provide for a corresponding increase in the length of the shoulder strip of the final coat-like product.
